COMBINATION TABLE AND BENCH STRUC-
TURE AND TEETER-TOTTER

Peter Schladermundt, Bronxville, N. Y.

Application April 26, 1947, Serial No. 744,057

1 Claim. (Cl. 155—41)

1

The present invention relates to table and bench structures and teeter totters and, more particularly, to such a structure adapted for children which may alternately serve as a table and bench structure and a teeter totter upon simple manipulation.

The general object of the present invention is to provide such a structure which is sturdy and of simple construction, may be economically produced and which may be manipulated in one simple manner to serve as a solid table and bench unit free from tendency to dangerous collapse and which, when again manipulated in another simple manner, may be converted into a strong and safe teeter totter that will effectively support little tots during rocking action without danger of them tumbling off backwards.

A more specific object of the invention is to provide such a structure characterized by a frame supporting a table top associated with suitable rocker means intermediate bench seats equipped with pivoted backs which may be easily swung down to and latched in supporting positions to cooperate with the rocker means in effectively holding the table and benches in a rigid position, with the seat backs also adapted readily to be swung upwardly at will and again latched so that the structure is then supported solely on the rocker means to serve as a teeter totter with the seat backs providing security during rocking motion.

Other objects of the invention will in part be obvious and will in part appear hereinafter.

The invention accordingly comprises the features of construction, combination of elements and arrangement of parts, which will be exemplified in the construction hereinafter set forth, and the scope of the invention will be indicated in the claims.

For a fuller understanding of the nature and objects of the invention, reference should be had to the following detailed description taken in connection with the accompanying drawing, in which:

Fig. 1 is a side elevational view of an embodiment of the present invention showing in full lines the positions of the seat backs and associated parts when swung down to and latched in supporting positions so that the unit serves as a rigid bench and table unit, and also showing in dotted lines the positions of the seat backs and latching means when swung up and again latched to serve as back rests with the structure converted into a teeter totter; and

2

Fig. 2 is a bottom plan view of the structure shown in Fig. 1.

The embodiment of the present invention shown in the drawing comprises a frame structure preferably including two laterally extending, bowed side rails 10, 10. On the outsides of the medial portions of the side rails 10, 10 are fixed a pair of transversely spaced apart rockers 11, 11 by any suitable means, such as through bolts 12, 12, and with a bridge piece or brace 13 mounted between the side rails. As will be seen from Fig. 1 each rocker 11 has the bottom end 14 thereof curved to rock over a floor or other laterally extending supporting surface, diagrammatically indicated at 15. The top end 16 of each rocker 11 has a pair of transversely extending holes therein receiving pins 17, 17 mounted in the ends of transversely extending cross braces 18, 18 positioned between the top ends of the two rockers. A table top 19 is mounted in a lateral position upon the top ends 16, 16 of the rockers 11, 11 by any suitable means, such as by the cross braces 18, 18 to which the table top may be fastened by screws 20, 20.

On each end of the frame structure provided by the pair of side rails 10, 10 is securely mounted a bench seat 21 by any suitable means, such as screws 22, 22. The back end 23 of each bench seat 21 has pivoted thereto on opposite sides angle brackets 24, 24. Each angle bracket 24 preferably has a relatively short arm 25 pivotally mounted at 26 to the edge of the seat 21 and a relatively long arm 27 extending at an angle to the short arm 25 and fastened by any suitable means to an edge of a seat back 28. Each seat back 28 is thus fixed between the long arms 27, 27 of one pair of cooperating angle brackets 24, 24. For this purpose screws 29, 29 may be employed in cooperation with headed studs or nails 30, 30, with each of the latter having its head extending laterally a short distance out away from the outer face of angle bracket arm 27.

Each bench seat 21 has pivoted to the sides thereof at 31, 31 a pair of latch brackets 32, 32. Each latch bracket 32 preferably comprises an elongated member or arm as shown, having one end thereof pivoted to an edge of the bench seat 21 at 31 and the other end provided with a pair of holes 33 and 34 for alternate engagement therein of the extending head of stud 30 when the seat back is swung either down to the full line position or up to the dotted line position shown in Fig. 1. Of course, holes 33, 33 and 34, 34 are at least slightly larger than the heads of

studs 30, 30 readily to receive the latter as will be apparent to one skilled in the art.

In operation, the embodiment of the present invention shown in the drawing may serve as a rigid bench and table unit when the seat backs 28, 28 are swung down to the full line positions shown in Fig. 1, with the top ends of those seat backs swung back beneath the back ends 23, 23 of the bench seats 21, 21 for secure support. The latch arms 32, 32 at each end of the frame are swung down to the full line positions and the headed studs 30, 30 are engaged in the holes 33, 33, detachably to latch the two seat backs 28, 28 in those structure-supporting positions. As shown in Fig. 1, the distance between the crown of the curved end 14 of each rocker 11 at 35 and the top edge of the adjacent side rail 10 is substantially equal to the length of each seat back 28, so that the two rockers and the two seat backs cooperate to support the bench and table unit upon a laterally extending surface 15.

When it is desired to convert the rigid table and bench unit into a teeter totter, each of the four latch arms 32, 32 are flexed laterally to disengage the headed studs 30, 30 from the latch arm holes 33, 33 with those heads carefully aligned with the holes. The seat backs 28, 28 are then swung outwardly up to the dotted line positions shown in Fig. 1, and the latch arms 32, 32 are swung up so as to engage the headed studs 30, 30 in the latch arm holes 34, 34. Thus the seat backs 28, 28 are detachably latched in the dotted line positions shown in Fig. 1, so that the apparatus may serve as a teeter totter with the seat backs providing a measure of safety for the occupants.

It will thus be seen that the objects set forth above and those made apparent in the preceding description are efficiently attained and, since certain changes may be made in the above construction and different embodiments of the invention could be made without departing from the scope thereof, it is intended that all matter contained in the above description or shown in the accompanying drawing shall be interpreted as illustrative and not in a limiting sense.

It is also to be understood that the following claims are intended to cover all of the generic and specific features of the invention herein de-

scribed, and all statements of the scope of the invention which, as a matter of language, might be said to fall therebetween.

Having described my invention, what I claim as new and desire to secure by Letters Patent is:

A combination table and bench structure and teeter totter comprising, in combination, an elongated frame structure, a table top medially mounted on said frame structure, a pair of bench seats mounted on opposite ends of said frame structure, rocker means of certain elevation for medial support of said frame structure, two pairs of angle brackets with each pair having laterally extending arms pivotally mounted on the back end of one of said bench seats and with each bracket having another arm extending at an angle to the pivoted arm thereof, a pair of seat backs each fixed between the angular arms of one pair of said angle brackets to be pivoted thereby between two positions, the two positions respectively being a downwardly extending frame-supporting position with the bracket-supported end of each of said seat backs swung under the back end of its bench seat whereby the latter rests on that seat back end and an upwardly extending back-supporting position with the bracket-supported end swung up to behind the back end of its bench seat, and two pairs of latch arms with each pair having ends thereof pivotally mounted on one of said bench seats and the other ends thereof adapted to be swung up and down detachably to engage and latch the adjacent seat back in either of its two positions, each seat back being of such length as cooperatively to engage with said rocker means a laterally extending surface to support together said frame structure in a substantially lateral position.

PETER SCHLADERMUNDT.
